DISPENSING HEAD FOR COLLAPSIBLE
TUBES AND THE LIKECharles Stewart Mann, Vancouver, British
Columbia, Canada

Application September 13, 1937, Serial No. 163,568

7 Claims. (Cl. 221—60)

My invention relates to improvements in dispensing heads for collapsible tubes and the like. The objects of the invention are to provide means whereby tooth paste or shaving cream and the like may be dispensed in suitable quantity from a collapsible tube and the orifice through which the paste is discharged shut off in response to thumb pressure upon the head; to provide means whereby the opening of the device for dispensing is accomplished by a turn of the head in one direction of 180 degrees or less, so that the tube can be held and the head manipulated by one hand if desired. A further object is to provide a structure which will preclude the entry of bacteria. A still further object of the invention is to provide means whereby the extrusion of paste is automatically shut off and the orifice is closed and hermetically sealed in response to thumb pressure.

20 The invention consists essentially of a sleeve adapted for attachment to the nipple of a collapsible tube, a cap rotatable upon the sleeve and having a discharge orifice and a closure for the orifice which is adapted to be withdrawn from the orifice in response to a partial turn of the cap to permit the flow of paste material therethrough, as will be more fully described in the following specification and shown in the accompanying drawing, in which:

30 Fig. 1 is a sectional view of the invention showing part in elevation.

Fig. 2 is a reduced scale plan view of the spiral slotted sleeve showing its connection to the main sleeve.

35 Fig. 3 is a reduced scale plan view looking up, of the vertical slot sleeve showing its connection to the cap.

Fig. 4 is a projected elevational view of the slotted sleeve opened out to show the shape of 40 the plunger retracting slots.

Fig. 5 is a front view of the plunger.

In the drawing like characters of reference indicate corresponding parts in each figure.

The numeral 1 indicates a collapsible tube of the usual type having conical shoulders 2 and a nipple 3 provided with the usual thread 4. Secured to the nipple 3 is an adapter 5 consisting of an internally and externally threaded collar 6 provided at intervals of its periphery with apertures 7 which are in alignment with its internal thread. Extending outwardly from the base of the collar is a conical flange 8 which is adapted to cover the shoulders 2 of the tube 1. The adapter 5 is not an essential to the invention, 55 but is a convenience inasmuch as with different

sizes of tubes a dispensing head of one size may be used on tubes of different sizes.

Screwed onto the adapter 5, or alternately onto the nipple 3, is a base or main sleeve 9 which is held against rotation by a grub screw 10 having a point which enters the metal of the nipple 3 after passing through one of the apertures 7 in the adapter. The main sleeve is provided with an internal flange 11 which is drawn down onto a packing washer 12 carried upon the end of the nipple 3 and the adapter 5 to prevent extrusion of the paste. A groove 13 is formed on the outer periphery of the main sleeve and is fitted with a packing 14, an annular groove 15 is formed on the main sleeve, the purpose of which will hereinafter appear.

Fitted upon the upper extremity of the main sleeve 9 is a non-rotatable sleeve 16 having a plurality of spiral segmental slots 17 equidistantly spaced about its wall. This sleeve will be hereinafter referred to as the spiral slot sleeve. The slots 17 are each provided with an upper and a lower horizontal portion respectively numbered 18 and 19, the purpose of which will hereinafter appear. Projecting radially from the base of the spiral slot sleeve 16 are radial arms 20, see Figure 2, connecting with a peripheral rim 21 which is recessed into the upper face of the main sleeve 9 and secured in position by pins 21A. Rotatably mounted within the spiral slot sleeve 16 is a vertical slot sleeve 22, so called because it is provided with a single vertical slot 23 in its periphery. The slot 23 is of the same length as the vertical length of any of the slots 17 plus their horizontal portions 18 and 19. The sleeve 22 is provided at its upper end with T-headed radial arms 24, the ends of which are embedded in complementary recesses 25 formed in the wall of a cap 26 and are preferably secured therein.

The cap 26 is provided with a central orifice 27 having tapered side walls substantially forming a valve seat 28 and is provided with a projecting band 29 about its periphery which is preferably knurled to afford a grip for turning. The cap is provided at its base with a skirt 30 which fits over the main sleeve 9 and has at its lower extremity a bevelled tongue 31 which rides in a groove 32 formed in the conical flange 8. The cap is rotatably held in position by one or more grub screws 33 which pass through the skirt 30 and enter the groove 15 of the main sleeve. An opening 34 is formed in the skirt 30 to admit the grub screw 10 into its position and so that this grub screw and the opening 34 may be easily brought into register. The skirt 30 and the

flange 8 are provided with complementary markings 35 of any suitable type.

Mounted in the base of the vertical slot sleeve 22 is a screw 36 which carries a post 37 surrounded by a compression spring 38 and slidably mounted in the sleeve 22 is a hollow plunger 39 which is preferably stamped out of sheet metal and provided in its side wall with an integral spring 40 having at its lower end a button 41 which projects through the vertical slot 23 and into any one of the spiral slots 17 or their horizontal portions 18 and 19. The diameter of the button 41 is equal to the width of any of the slots 17 and the slot 23 and is equal also to the vertical height of the portions 18 and 19. The upper end of the plunger 39 forms a closure 42 for the valve seat 28 and when entered therein prevents extrusion of the paste or intrusion of unwanted matter, at the same time leaving the end of the cap capable of being cleaned and dried. The spring 38 bears upwardly against the plunger to force it upwards when the button 41 is released from the horizontal portion 19 of any of the slots 17.

Mounted in the cap 26 is a push button generally indicated by the numeral 43 which consists of a stem 44 having adjacent its inner end a conical stop 45 which prevents the outward movement of the stem beyond a predetermined point 30 and spreads the paste in which it is operating to ensure the return of the stem to its predetermined normal position and prevents the stem from pumping. A packing gland 46 surrounds the stem to prevent paste leakage therearound and is housed in a threaded bushing 47 to facilitate removal of the push button assembly. The button 41 when the head is closed would be at the top of the vertical slot 23 and in the upper horizontal portion 18 of one of the slots 17. To open the head to dispense paste from the tube 1 the cap 26 is turned to the left one third of a turn. As the cap with its connected vertical slot sleeve 22 is turned, the button 41 will be drawn along the spiral slot 17 of the non-rotatable sleeve 16 down to the lower horizontal portion 19, thus withdrawing the plunger and its valve closure 42 from the orifice 27. When the cap is turned to its limit the button 41 will be in the lower horizontal portion 19 of its slot 17 and will be directly opposite the push button stem 44. When the button 41 is in a horizontal portion 19 the plunger 39 is retracted to the position shown in Figure 1 and the orifice 27 is open to permit paste to be dispensed. The plunger is incapable of movement in either direction when in full open or closed position, because the button 41 is then locked in one of the horizontal portions 18 or 19 of one of the slots 17. When sufficient paste has been squeezed out of the tube 1 through the orifice 27, thumb pressure upon the button 43 will thrust the button 41 out of its horizontal slot portion 19 so that the plunger 39 will be thrust upwardly by the spring 38 and close the orifice 27. On reaching the closed position the button 41 will register with and enter the horizontal portion 18 of the next adjacent slot 17, thus locking the head securely and leaving the cap in position to be again turned to retract the plunger. Obviously each third turn of the cap will retract the plunger and when the plunger has been returned to closed position a very slight rotational movement of the cap is required to again start the plunger downward.

It will be obvious that any number of spiral slots 17 may be provided in the slotted sleeve and

the turning movement of the cap to the extent of any one slot will suffice to retract the plunger.

What I claim as my invention is:

1. In a dispensing head for collapsible tubes, a main sleeve, a cap rotatable about the sleeve, said cap having a discharge orifice and a spring pressed button, a plunger normally urged to close the discharge orifice and means as the cap is turned in one direction to retract the plunger to open the discharge orifice, said means cooperating with the spring pressed button to release the plunger and permit it to return to closed position. 10

2. A dispensing head for collapsible tubes comprising a main sleeve, a cap rotatable thereon, a vertical slot sleeve inside the cap and rotatable therewith, a stationary spiral slot sleeve surrounding the vertical slot sleeve, said slot sleeves being of smaller diameter than the main sleeve to define a paste passage therearound, the vertical slot sleeve having a vertical slot in its periphery, said spiral slot sleeve having a plurality of spiral slots in its periphery, said cap having a discharge orifice, a plunger slidable within the vertical slot sleeve and having a retractile button normally projecting through the vertical slot and into one of the spiral slots of the spiral slot sleeve, means for urging the plunger upwardly to close the discharge orifice and means carried by the cap for releasing the button from its spiral slot and 30 means for urging the button into the next successive spiral slot. 20

3. In a dispensing head for collapsible tubes, a main sleeve, a cap rotatable about the sleeve, said cap having a discharge orifice and a spring 35 pressed button, a plunger normally urged to close the discharge orifice, a spiral slot sleeve and a vertical slot sleeve rotatable within the last mentioned sleeve, a plunger endwise movable within the vertical slot sleeve, and means extending 40 from the plunger engaging the spiral slot and the vertical slot sleeve whereby the rotation of the vertical slot sleeve within the spiral slot sleeve withdraws the plunger from the orifice. 40

4. In a dispensing head for collapsible tubes having a main sleeve and a cap rotatable about the main sleeve provided with a discharge orifice, a stationary and a rotatable sleeve within the cap, one of said sleeves being provided with a vertical slot and one with a plurality of progressively arranged spiral slots, each of said spiral slots having an upper and a lower horizontal portion, the upper portion of one slot and the lower portion of the next progressive slot being one above the other, a plunger slidable concentrically within 55 the sleeves adapted to normally close the orifice in the cap, spring means for moving the plunger to close the orifice, a member projecting transversely from the plunger adapted to slide within the vertical slot and progressively in the spiral slots, said member being adapted to project into a horizontal upper portion of a spiral slot when the plunger is in orifice closing position and to move into a horizontal lower portion when the plunger is fully withdrawn, and means rotatable 60 with the cap for displacing the member from its spiral slot. 55

5. A dispensing head for collapsible tubes comprising a sleeve and a cap rotatable upon the sleeve, said cap having a discharge opening, a plunger movable endwise of the sleeve and the cap adapted to be retracted inwardly from the orifice in response to turning the cap about the sleeve, a spring pressed button for releasing the 70 75

plunger when retracted, and means for urging the plunger outwardly to close the orifice.

6. In a dispensing head for collapsible tubes having a main sleeve, a cap rotatable upon the sleeve provided with a discharge orifice, a plunger endwise movable within the cap to close the orifice, a projecting member upon the plunger and a pair of slotted sleeves cooperating with the projecting member as the cap is rotated to withdraw the plunger inwardly from the orifice, one of said slotted sleeves being connected with the cap to rotate therewith and the second of said slotted sleeves being held against rotation and a spring for urging the plunger to close the orifice. 5
- 5
- 10 draw the plunger inwardly from the orifice, said plunger being provided with a spring extending longitudinally thereof.
7. In a dispensing head for collapsible tubes

having a main sleeve, a cap rotatable upon the sleeve provided with a discharge orifice, a plunger endwise movable within the cap to close the orifice, a projecting member upon the plunger and a pair of slotted sleeves cooperating with the projecting member as the cap is rotated to withdraw the plunger inwardly from the orifice, one of said slotted sleeves being connected with the cap to rotate therewith and the second of said slotted sleeves being held against rotation and a 10 spring for urging the plunger to close the orifice.
